US00D585070S

(12) **United States Design Patent**
Sugitani et al.

(10) **Patent No.:** US D585,070 S
(45) **Date of Patent:** ** Jan. 20, 2009

(54) **SCANNER**

(75) Inventors: **Minoru Sugitani**, Kahoku (JP); **Takashi Kondo**, Musashino (JP)

(73) Assignee: **PFU Limited**, Ishikawa (JP)

(**) Term: **14 Years**

(21) Appl. No.: **29/300,044**

(22) Filed: **Feb. 13, 2008**

(51) **LOC (9) Cl.** **14-02**

(52) **U.S. Cl.** **D14/453; D14/422**
